UNITED STATES PATENT OFFICE.

E. A. GOODES, OF PHILADELPHIA, PENNSYLVANIA.

IMPROVED STAIR-ROD FASTENING.

Specification forming part of Letters Patent No. 40,339, dated October 20, 1863.

To all whom it may concern:

Be it known that I, E. A. GOODES, of Philadelphia, Pennsylvania, have invented an Improved Fastener for Stair-Rods; and I do hereby declare the following to be a full, clear, and exact description of the same, reference being had to the accompanying drawings, and to the letters of reference marked thereon.

My invention consists of two levers, each having two cam-like projections constructed and applied to the fastening of a rod for confining a narrow carpet to the step of a stair, substantially as described hereinafter; and my invention further consists of fasteners for confining a broad carpet to the step of a stair, the said fastener being a combination of the said levers and their cam-like projections with certain brackets applied to the stairs, substantially as described hereinafter.

The object of my invention is to produce cheap, simple, and durable fasteners, by the aid of which stair-rods can be secured with facility to and readily removed from the stairs.

In order to enable others to make and use my invention, I will now proceed to describe the manner of constructing and applying the same.

On reference to the accompanying drawings, which form a part of this specification, Figure 1 is a longitudinal section of a stair-rod with my improved fastener; Fig. 2, a transverse section of Fig. 1, illustrating the relative position of fastener and rod prior to the latter being secured; Fig. 3, a transverse section on the line 1 2, Fig. 1; Fig. 4, a longitudinal section of a stair-rod with a modification of my improved fastener; Fig. 5, a transverse section on the line 3 4, Fig. 2; and Fig. 6, a sectional plan on the line 5 6, Fig. 2.

On reference to Figs. 1, 2, and 3, A represents the stair-rod, which consists, as usual, of a metal plate bent to the form illustrated in the transverse sections, Figs. 2 and 3, so that there may be two longitudinal grooves, *d d*, in the inside of the rod.

Two bent levers, B and B', are hung, each by means of a suitable screw or bolt, *e*, to the vertical portion of the step, which is represented by the line C, Fig. 3, and each lever is provided with two cam-like projections, *c c*, having rounded ends.

When the stair-rod has to be secured to the step, the two levers are, in the first instance, elevated to the positions shown by red lines, Fig. 1, after which the rod is placed directly against the step of the stair in front of the carpet, when the two cam-like projections of the levers will occupy the positions within the rod seen in Fig. 2, the levers themselves bearing against the step. After this the levers are depressed to the position shown by the black lines, Fig. 1, thereby causing the cam-like projections *c c* to become jammed, one against the inside of the upper longitudinal groove, *d*, of the stair-rod, and the other against the inside of the lower longitudinal groove of the rod, as seen in Fig. 3. The rod is thus effectually secured.

It should be understood that the above-described stair-rod fasteners are used when the carpet is narrower than the stairs, the width of the stairs being in Fig. 1 represented by the two black lines D and D', and the width of the carpet by the two red lines *x x*.

When the carpet has to be of the same width or nearly the same width as the stairs, I adopt the modified fastener represented by Figs. 4, 5, and 6, the levers B and B', with projections *c c*, similar to those above described, being used in this modification; but instead of being hung directly to the front of the step, as in the former case, they are connected each to a bracket, E, one bracket being secured to one side, D, of the stair and the other to the opposite side, D', in the position best observed in the sectional plan view, Fig. 6, so that the carpet may take its place between the bracket and the front C of the step.

The method of securing the rod in this modification of my fastener by the levers B and B' and their cam-like projections needs no further description.

It will be observed that each of the levers is provided at the outside end with a lip, *a*, which serves the twofold purpose of preventing the levers from being depressed beyond a given point and of affording a projection, by means of which the levers can be readily raised when the stair-rod has to be removed.

The advantages of my improved fasteners may be described as follows: First, they are cheap and simple as regards construction, being readily cut or stamped out from sheet

metal; secondly, they are not exposed to view when the rods are in their places, and are therefore not liable to be tampered with by children; thirdly, they afford greater facilities for readily removing and replacing the rods than ordinary fasteners, into which the rods have to be pushed endwise; and, fourthly, they confine the rods more securely than fastenings of the ordinary construction.

I claim as my invention and desire to secure by Letters Patent—

1. The levers B and B', with their cam-like projections *c c*, constructed and applied to the

fastening of stair-rods, substantially as and for the purpose described.

2. In combination with the said levers B and B' and their cam-like projections *c c*, the brackets E applied to the stairs, substantially as described, for the purpose specified.

In testimony whereof I have signed my name to this specification in the presence of two subscribing witnesses.

E. A. GOODES.
